UNITED STATES PATENT OFFICE.

WILLIAM F. MURPHY, OF IOWA CITY, IOWA.

HANGER FOR ELECTRIC LAMPS.

SPECIFICATION forming part of Letters Patent No. 642,623, dated February 6, 1900.

Application filed May 15, 1899. Serial No. 716,940. (No model.)

To all whom it may concern:

Be it known that I, WILLIAM F. MURPHY, a citizen of the United States, residing at Iowa City, in the county of Johnson and State of Iowa, have invented new and useful Improvements in Hangers for Electric Lamps, of which the following is a specification.

This invention relates to improvements in hangers for electric lamps and other electrical devices; and it has for its prime object to increase the efficiency of such devices, while simplifying the construction and consequently obviating the liability of the parts getting out of order, the parts being so constructed and arranged that the drum around which the lamp-suspending cable is wound incloses and conceals from view the counterbalancing mechanism.

The invention and its many advantages will appear from the following description and claims when taken in connection with the annexed drawings, in which—

Figure 1 is a longitudinal vertical sectional view of my improved device with parts broken. Fig. 2 is a cross-sectional view through the ratchet with the other parts of one end of the device in elevation. Fig. 3 is a similar view of the opposite end of the device, and Fig. 4 is a perspective view of the counterbalancing mechanism with parts in section.

Referring by letter to said drawings, A and B indicate two brackets, which are here shown as secured to a ceiling and are designed to support a rotatable drum and its actuating mechanism. These brackets are connected with the main wires of an electric system, as shown at a, or with branch wires of such system in the usual manner. The bracket A is provided at the lower end of its depending branch with a transverse slot b, while the bracket B is provided at a corresponding point with a circular hole or aperture c to respectively receive the ends of rods which extend from the core surrounded by a coil or spiral spring, as will be presently described. The core for the spring is composed of two sections d and e of wood. The section d has secured to it the rod f, which terminates at its outer end in a flat portion g to fit the slot b of the bracket A and be prevented from turning therein. The rod h has its outer end round, so as to turn freely in the bearing-aperture c

of the bracket B. This rod passes through the section e of the core for the spring and extends into a socket i, which is arranged in 55 the core-section d. The core-section d may be fixed to the shaft or rod f by any suitable means, in the present illustration a cap j being employed for the purpose, so that said core-section d will be held stationary on the 60 rod f, while the section e may be left free.

c indicates a coiled spring which is shown of flat steel, although other makes might be employed. This spring encircles the core, which, as before stated, is formed in sections 65 and has one end secured to the fixed or immovable core-section, as shown at k, while the opposite end is secured to the rotatable rod h. I prefer to connect the opposite end of this spring to the rod h by providing said rod with 70 two fixed collars l and m, having a pin n extending across the space formed between the two and bending the end of the spring over this cross-pin, as shown at e'; but I do not wish to confine myself to this manner of making 75 the connection. By the construction described it will be seen that when the rod h has been turned in one direction it will coil and contract the spring upon the core and when turned in the opposite direction will allow the 80 spring to expand or weaken.

D indicates a drum the tube of which may be composed of fibrous board or other suitable material and is designed to have wound upon it the cable E, from which the lamp or other 85 electrical device is suspended. I provide each end of this drum with cheek plates or disks F. These plates may be composed of light sheet metal or other suitable material and may have their outer edges bent laterally, as 90 shown, while short branches q may be turned inwardly and pierced to receive screws r, whereby the same may be secured to the cylinder of the drum, one set of screws being used to also serve in connecting the cables E, 95 as better shown in Fig. 1 of the drawings. Fixed to or formed on the outer side of the right-hand disk is a pinion G, which meshes with a vertically-disposed gear-wheel H, which gear-wheel has a laterally-disposed 100 pinion I formed at its hub, and this gear, and consequently the pinion, has a bearing on a rod J, which extends inwardly from the bracket B. The pinion I in turn meshes with

a vertically-disposed gear K, which is fixed to the shaft or rod h. This gear K is shown as fixed to the rod h by means of a pin s taking through the hub of the gear and through a hole in the shaft. Other means might be employed for fixing the gear to the shaft or rod.

The bracket A is provided at its inner lower end and around the slot b with a series of recesses, so as to form a ratchet L, a dog or pawl M being pivoted to the outer side of the adjacent plate F to engage said ratchet and lock the drum at the desired point.

By the construction described it will be seen that the drum D will make several complete revolutions on the sectional rod or shaft before the spring C has made one complete revolution around the core. It will also be seen that by reason of the shaft being in two sections the parts may be held in proper relative positions and yet perfect freedom of action allowed to the drum and counterbalancing devices.

From the foregoing description the operation of my invention will be obvious. It will be seen that by drawing upon the cable E the dog or pawl will be first drawn out of the ratchet and then the cable may be unwound from the drum as the drum rotates in its bearings. The action of drawing the cable will, through the medium of the train of gearing, cause the shaft h to turn, which will in turn coil or contract the spring C upon the sectional core, so that when it is desirable to wind the cable E upon the drum it is simply necessary to draw upon the cable until again releasing the ratchet and then suddenly slacken pressure thereon, so as to allow the spring to act. By this means an incandescent lamp or other electrical device suspended from the cable may be raised or lowered to any desired position and held therein.

Having thus described my invention, what I claim is—

1. In a hanger for electrical devices, the combination of two brackets, a shaft or rod comprising a section fixed in one bracket and

a section journaled in the other bracket, a core-section mounted on the rotary section of the shaft or rod, a core-section fixed on the fixed section of the shaft or rod and having a 50 socket in its inner end receiving the other section of said shaft, the spiral spring surrounding the core-sections and connected at one end to the rotary section of the shaft or rod and at its opposite end to the fixed core-section, the drum, means for transmitting motion from the rotary shaft-section to the drum and vice versa, and means for locking the drum, substantially as specified.

2. In a hanger for electrical devices, the 60 combination with two brackets; of the sectional shaft or rod each section of which bears at one end in one of the brackets and one section being adapted to rotate while the other remains fixed, the cheek-plates, the drum, 65 the sectional core surrounding the sectional shaft or rod, the spiral spring secured at one end to one section of the shaft or rod and at its opposite end to one core-section, a train of gearing connecting one section of the rod 70 with the drum, and a pawl and ratchet connecting the drum with one of the brackets, substantially as specified.

3. In a hanger for electrical devices, the rod or shaft comprising the sections f and h, the 75 core-section d, and the core-section e carried by the rods or shafts; in combination with the spring secured at one end to the core-section d and secured at its opposite end to the shaft or rod h, a drum inclosing the whole, 80 and a suitable means, (as a pawl and ratchet), for locking the drum against rotation, and a suspending-cable attached to the drum, substantially as specified.

In testimony whereof I have hereunto set 85 my hand in presence of two subscribing witnesses.

WILLIAM F. MURPHY.
